United States Patent Office.

JOSEPH G. RUST, OF XENIA, OHIO.

Letters Patent No. 75,580, dated March 17, 1868.

IMPROVED DEVICE FOR LASTING BOOTS AND SHOES.

The Schedule referred to in these Letters Patent and making part of the same.

Be it known that I, JOSEPH G. RUST, of Xenia, county of Greene, in the State of Ohio, have invented a new and useful Improvement on a Machine for "Lasting" Boots and Shoes, commonly called "Lasting-Pincers;" and I do hereby declare that the following is a full, clear, and exact description of the construction and operation of the same, reference being had to the annexed drawings, making a part of this specification, in which—

Figure 1 is a side view of the machine.

Figure 2, a side view of the piston D and lever H, composed of one bar.

Similar letters of reference indicate corresponding points.

This invention relates to a new and useful improvement on a machine or pincers for drawing the "upper leather" of a boot or shoe over the last, so that it may fit snugly thereto, which operation is technically termed "lasting."

The invention consists of two pairs of jaws connected together and operated by a semicircular lever, piston, and toggles, as hereinafter set forth.

A A, fig. 1, represent the two main or principal jaws of the device, which are curved in S-form, and have each a circular or oval loop, a, at their centre, one loop fitting within the other, and connected by a pivot, b. The upper ends of the jaws A A are connected by a toggle, B, to a nut, C, through which the piston D passes, said piston extending down through the loop a of the jaws A A, and having the middle joint of the toggle F fastened into its end by a pivot at E. The toggle F is connected with the upper end of the jaws G G, which are connected with the jaws A A by pivot c. Near the upper end of the piston D is a fulcrum, K, attached to its side, on which the under edge of the lever H presses and slides in operating the machine. The semicircular lever H is made of iron or other suitable metal, constructed in form as shown on the drawings, and consists usually of two bars of similar form, united at the handle I, with sufficient space between the two bars to allow the piston D to play between them, and the nut C to be embraced between the lower ends. This lever is attached to the nut C by means of pivots at each side, d. The upper edge of one bar of the lever is notched, so that when it is brought down, the click L will drop into a notch, and hold the machine in position. The lever may also be constructed of one semicircular bar, fig. 2, notched at the upper edge, and fastened to a projection of the nut C by means of a pivot, d, and work through a slot in the upper end of the piston D, and be fastened, when operating, by means of a click with eccentric-end, as in fig. 2. The lower ends of the jaws A A and G G are in line with each other, and it will be seen, by referring to fig. 1, that by taking hold of the lever H at the handle I, and bringing it down, the nut C will be raised, while the point of the piston at E will be moved down, which will cause the jaws G G to clamp together with the jaws A A, and at the same time the two pairs of jaws A A, G G will consequently be moved towards each other, and the leather firmly grasped at each side of the last, so that the "upper leather" of the boot or shoe may be stretched and drawn snugly over the last.

This implement may be manipulated with the greatest facility. It works with remarkable ease and perfection, and it will greatly expedite the work of lasting boots and shoes.

I disclaim the invention of the two pairs of jaws A A and G G, toggles B and F, and nut C, in the original invention of George Kemp, secured to him by Letters Patent, bearing date the 16th day of January, A. D. 1866.

What I claim as my invention, and desire to secure by Letters Patent, is—

The piston D, and the lever H and click L, in connection therewith, in combination with the piston D, all arranged substantially in the manner as and for the purposes herein set forth.

JOSEPH G. RUST.
